[57] **CLAIM**

The ornamental design for a combined low frequency muscle relaxer and storage case, as shown and described.

DESCRIPTION

FIG. 1 is a front view of a combined low frequency muscle relaxer and storage case show our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view thereof;

FIG. 8 is a cross sectional view thereof, taken along the line 8—8 of FIG. 1;

FIG. 9 is a perspective view thereof;

FIG. 10 is a perspective view thereof, with the electrodes in lid; and,

FIG. 11 is a perspective view thereof shown in use, the broken line showing of the leads and person is for illustrative purposes only and no part of the claimed design.

FIG.1

FIG. 2
